UNITED STATES PATENT OFFICE.

WILLIAM S. H. HAMILTON, OF SCHENECTADY, NEW YORK, ASSIGNOR TO GENERAL ELECTRIC COMPANY, A CORPORATION OF NEW YORK.

MOTOR CONTROLLER.

Application filed December 10, 1925. Serial No. 74,576.

This invention relates to the control of electric motors, and it relates more particularly to selective control systems suitable for use on electric locomotives or the like, where a plurality of driving motors are operated in various relations such as series, series parallel, and parallel during motoring and regenerative braking.

The general object of the invention is to provide an improved arrangement of control apparatus and circuits for controlling the interconnection of the motors in the various operating relations, as well as the connection of the motors to a power source, and the torque and speed of the motors in each relation during both motoring and braking operation.

While not limited thereto, a control system arranged in accordance with the present invention is particularly advantageous in controlling a three-speed, heavy traction electric locomotive. By means of the present invention, the several driving motors of the locomotive may be connected either in series relation for operation at relatively low speeds, in series-parallel groups for operation over an intermediate speed range or in parallel groups for high speed operation, depending upon the particular range of speed at which it is desired to operate the locomotive. Furthermore, as the service conditions vary, a transition of the motors either from a lower speed combination to a higher speed combination or from a higher speed combination to a lower speed combination readily may be accomplished without interrupting the continuity of the motor driving torque at any time. This is particularly advantageous when the electric locomotive is handling a train on a grade, where continuity of the motoring effect is essential to satisfactory operation. Otherwise the slack in the train may be bunched and then pulled out with sufficient force to break the couplers if the motoring effect is varied suddenly as necessarily occurs when the continuity of motoring operation is interrupted during transition from one speed combination to a different speed combination.

Briefly, in carrying this feature of the present invention into effect in a preferred form, the interconnection of the motors in the various speed relations is controlled through the agency of a pair of separately operable controllers, one for selecting the speed combination and the other for regulating the torque and consequently the speed of the motors in each of the speed combinations. With direct current, series wound driving motors, the speed controller is arranged to be operated progressively through a series of positions to control the resistors in the motor circuits so as to remove or insert the resistance in a series of steps to increase or decrease the motor torque and speed while operating in each speed combination. The pair of controllers are arranged to cooperate in controlling suitable power actuated motor switches so that the particular speed combination in which the motors are to operate may be pre-selected by operation of the selective controller, and then actually established upon a predetermined operation of the other controller to regulate the operating torque and speed of the motors in each combination to proper values. In this manner, the interconnection and driving torque of the motors may be changed at will so as to either accelerate or decelerate the locomotive smoothly and gradually even under the most severe operating conditions. Regenerative braking and reversing of the motors in each speed combination are under the control of additional separately operable controllers.

Control of the torque and speed of the motors in the series, the series-parallel, and the parallel speed combinations (as pre-selected by operation of the selective controller) is accomplished by operating the speed controller through the same series of positions. However, it is necessary for satisfactory and efficient control of the locomotive that the resulting variation in the motor torque occur in substantially equal increments upon operation of the speed controller between corresponding positions with the motors connected in each relation. This is accomplished in accordance with my invention by so organizing the resistor control arrangement that different amounts of the resistance are removed or inserted in the motor circuit at the same positions of the speed controller depending upon the particular relation in which the motors are operating. Thus the proper amount of resistance is inserted in or removed from the motor circuit

upon operation of the speed controller through the same series of positions to cause the motor torque to vary in substantially equal increments in each speed relation.

5 In general, a locomotive motor control system embodying my invention has the following advantageous features:

1. The motors can be accelerated successively through the series relation, the series-parallel relation, and the full parallel relation, as well as decelerated through the several relations in reverse order without breaking the continuity of motoring torque at any time.

15 2. The motoring torque can be varied in substantially equal increments in each operating relation of the motors.

3. The motors can be connected initially in either the parallel or the series-parallel relation without passing through a lower combination.

20 4. Likewise, the motor circuit can be interrupted in either the parallel or the series-parallel relation without passing through a lower combination.

30 5. The desired operating relation of the motors may be preselected at any time with the motors either at rest, coasting, or operating in any other combination by operating the selective controller, and the transition into the selected relation and the acceleration or deceleration of the motors in each relation is accomplished upon proper operation of the main speed controller.

35 A preferred form of the invention may be carried into effect in a control system for a three-speed, six-motor, electric locomotive as illustrated in the accompanying drawings.

40 Fig. 1 is a simplified schematic diagram of the driving motor circuits and the main control switches therefor.

Fig. 2 is a similar circuit diagram showing the arrangement of the controlling switch mechanism more in detail.

45 Fig. 3 is a chart indicating the sequence in which the various switches shown in Figs. 1 and 2 are operated to produce the various motoring, braking, and transition connections of the motors.

50 Fig. 4 is a diagram showing the control circuits for the several electrically controlled switches indicated in Figs. 1 and 2, together with the developments of the several manually operated master controllers, as well as 55 the electrical interlocks for insuring the desired operation of the switching system.

Figs. 5 and 6 are detailed views of the 60 manual operating handle and stop mechanism with which the main controller is provided.

Fig. 8 is a schematic diagram showing the 65 connections for initiating series parallel motoring operation from rest.

Fig. 9 is a schematic diagram showing the connections for initiating parallel motoring operation from rest.

Fig. 10 is a schematic diagram showing the connections for series parallel motoring operation following operation in other relations.

Fig. 11 is a schematic diagram showing the connections for full series regenerative braking operation.

Fig. 12 is a schematic diagram showing the connections for series parallel regenerative braking operation.

Fig. 13 is a schematic diagram showing the connections for parallel regenerative braking operation.

Figs. 14, 15, 16 and 17 schematically illustrate the manner in which transition of the motors from the parallel relation to the series parallel relation is accomplished without interrupting the continuity of the motor driving torque at any time.

Main motor circuits and switches.

As schematically shown in Fig. 1, the armatures $A_1, A_2, A_3, A_4, A_5, A_6$, together with the corresponding series field windings $F_1, F_2, F_3, F_4, F_5, F_6$, of the six locomotive driving motors are arranged to receive power from the trolley T through the circuit interrupter CB during motoring operation and return power thereto when the motors are over-excited by means of the exciter generator E to produce regenerative braking operation. The current in the motor circuit during both motoring and braking operation is regulated by the several groups of resistors R_{11} to R_{17} ; R_{21} to R_{25} ; and R_{31} to R_{35} ; which respectively are under the control of the switches 11 to 17, 21 to 25, and 31 to 35.

The interconnection of the driving motors in series relation for low speed operation, as well as in series-parallel relation with three motor in each of two parallel connected groups for intermediate speed operation, and in series-parallel relation with two motors in each of three parallel connected groups for high speed operation, is controlled by the line switches 1 to 10 and the cooperating series-parallel switches 41 to 58 as will be described more fully hereinafter.

The interconnection of the driving motors in the several speed relations just described is old and well-known, and for convenience will be termed simply "series relation", "series-parallel relation", and "parallel relation" respectively.

The line switches 1 to 10, and also the resistance controlling switches 11 to 17, 21 to 25, 31 to 35, preferably are of the electromagnetic contactor type, as indicated by full circles in the drawings and shown more in detail in Fig. 2. The cooperating series parallel switches 41 to 58 may be actuated

by cams which are operated by means of an electrically controlled pneumatic motor. Preferably the pneumatically operated cam contactors 41 to 58 constitute an electrically controlled, pneumatically actuated, series-parallel switch of the form illustrated and described in Patent No. 1,267,817, issued to R. Stearns and myself, although other forms of series-parallel switching apparatus 10 may be employed, if desired. It will be observed that the series-parallel switches 44, 46, and 52 control a short circuit around the resistors R_{44} , R_{46} and R_{52} , respectively, so as to insert these resistors in the circuit 15 during certain transitions.

In accordance with modern practice, the field windings of the driving motors are shunted to produce maximum speed operation during series, series-parallel and parallel motoring operation. For this purpose the switches 71, 72 are arranged to control the shunting resistors R_{71} and R_{72} for the field windings F_5 and F_6 , and the switches 73 and 74, 75 and 76; and 77 and 78; for 20 the field windings F_4 ; F_3 ; F_1 and F_2 respectively. As indicated in the drawing, the several shunting resistors R_{71} , R_{73} , R_{75} , R_{77} , may be of the inductive type in order to 25 compensate for the inductance of the respective motor field windings with which the resistors are associated. The shunting switches 71 to 78 preferably are of the electromagnetic contactor type similar to the line and resistance controlling contactors 30 previously described.

The switches 61 to 64 indicated in the drawing as open squares establish ground connections for the motors through the resistors R_{61} , R_{62} , R_{63} , R_{64} respectively during 40 regenerative braking operation and the switches 65, 67, 69 and 70, also indicated as squares in the drawing, are employed in establishing the regenerative braking connections. The several braking switches 45 preferably are of the cam type and are operated by a suitable electrically controlled pneumatic engine in a manner similar to the operation of the pneumatic cam operated series-parallel switch previously mentioned.

50 Fig. 2 shows more in detail the preferred construction and circuit connections of the various electromagnetic and cam actuated controlling switching apparatus schematically indicated in Fig. 1 and no further detailed description thereof is deemed necessary as it will be apparent to those skilled in the art that switches of other types and forms may be employed if desired. A reversing switch indicated as Rev. Sw. is provided for reversing 55 the direction of current flow through the motor field windings in order to reverse the direction of rotation of the driving motors. The reversing switch is preferably of the drum type with stationary fingers cooperat- 60 ing with movable contact segments which are

65 moved by a pneumatic motor under the control of the electromagnetic valves 80 and 81 indicated in Fig. 2. Separate energization of the magnet valves 80 and 81 serves to effect operation of the reversing switch to 70 the forward and reverse positions respectively.

75 Consideration of the chart in Fig. 3, showing the sequence in which the various control switches are closed during operation of the motors in the several relations may be deferred until the operation of the control system is set forth.

Control circuits and switches.

80 Referring now to Fig. 4 which diagrammatically illustrates the manually operated master controllers, together with the control circuits for the electrically controlled motor switches shown in Figs. 1 and 2, it will be 85 seen that the reversing controller Rev. C. is arranged to control the energization of the magnet valve windings 80 and 81 of the pneumatically actuated reversing switch, Rev. Sw., so as to operate the same to 90 the forward and the reverse positions respectively.

95 The selective controller, Sel. C., is provided with suitable segments for controlling the energization of the double coil operating windings 82 and 83 of the series-parallel switch, S. P. Sw., in order to operate the latter to either the series position indicated as *s*, the series-parallel position indicated as *s. p.*, or the parallel position indicated as *p* 100 in the drawing. The magnet valves of the pneumatic engine which actuates the operating cams of the series parallel contactors 41 to 58 are provided with double coil operating windings merely for the purpose of simplifying the control circuits, and energization of either of the windings 82 serves to cause 105 operation of the series-parallel switch in the parallel to series direction, while energization of either winding 83 causes operation in the series to parallel direction. In order to stop the series parallel switch in the intermediate series-parallel position a winding 82 and a winding 83 are simultaneously energized, thus balancing the 110 opposing actuating pistons of the pneumatic engine.

115 The main controller M. C. is provided with suitably spaced segments for successively controlling the energizing circuits of 120 the electromagnetic resistance contactors 11 to 17, 21 to 25, and 31 to 35, previously described in connection with Figs. 1 and 2, and of which only the operating windings are shown diagrammatically in Fig. 4 and 125 identified by the same numerals as the corresponding contactors. The arrangement of the electrical interlocking segments whereby the main controller cooperates with the selective controller in controlling the series- 130

parallel switch to effect transition of the motors during acceleration and deceleration of the locomotive will be best understood from the description of the operation of the control system given hereafter.

The braking control Br. C. is arranged to control the energization of the operating windings 84 and 85 of the braking switch Br. Sw., and also the operating winding 86 of the electromagnetic switch which controls the energizing circuit for the shunt field winding of the exciter generator E shown in Figs. 1 and 2 and indicated in Fig. 4 as Ex. S. F. The windings 84 and 85 control the magnet valves of the pneumatic engine which operates the cam contacts 61-70 of the braking switch from the motoring to the series, and series-parallel; and parallel braking positions and from the braking to the motoring position respectively.

With my improved control system, the mechanical interlocking required for insuring proper operation of the several controllers is reduced to a minimum. For single end control the only mechanical interlocking is between the reversing controller and the main controller. In accordance with standard practice, these controllers are interlocked so as to prevent operation of the reversing controller when the main controller is in any position except the off position. If double end control is desired, the braking controller may be mechanically interlocked with the main controller to prevent operation of the reversing controller to the "off" position unless the braking controller is in the normal or motoring position.

It will be observed that several of the electromagnetic line and resistance controlling contactors are provided with auxiliary interlocking contacts which are shown in Fig. 4 in proximity to the operating windings of the contactors and are identified in the drawing by the number of the contactor with the subscript *a*, *b*, *c*, etc. The series-parallel switch and also the braking switch are provided with a plurality of auxiliary electrical interlocking segments as will be apparent from the drawing. The purpose and arrangement of these interlocking segments will be apparent from the operation of the system. The interlocking relays R_1 and R_2 cooperate with the selective controller Sel. C. and the main controller M. C. in causing operation of the control system to effect transition of the motor connections in a manner which also will be described more fully hereinafter in connection with the operation of the system. Each of the relays R_1 and R_2 are of the electromagnetic type and the relay contacts are biased to the positions in which they are shown.

The main line circuit breaker C. B. through which the motors receive current from the trolley T as shown in Figs. 1 and 2 is oper-

ated to the closed position by the resetting electromagnet 88 which is controlled by the push button P. B. Preferably the circuit breaker C. B. is biased to the open position and is held in the closed position under the control of a holding winding 87 which may be energized through a circuit including the contacts of suitable overload relays indicated in the drawing O. L.—1, 2, 3, and also the contacts of an overvoltage relay indicated as O. V. The switch 79 also may be included in the circuit of the holding winding 87 and conveniently located with respect to the locomotive operator in order to permit manual tripping of the circuit breaker C. B. whenever desired.

Series operation.

Ordinarily it is desirable to start the locomotive with the driving motors connected in the series relation in order more easily to control the motor current and torque in accelerating a train. The manipulation of the master controllers shown in Fig. 4 and the response of the electric switches controlled thereby in effecting an acceleration of the locomotive with the motors in the series connection and in the forward direction is as follows: The circuit breaker CB is closed by operating the push button PB. The reversing controller Rev. C. is operated to the forward position, the selective controller Sel. C. is moved to the series position, and the main controller is advanced to its first operative position indicated as *p*—1. This establishes an energizing circuit for the magnet valve winding 80 of the motor reversing switch pneumatic engine, the circuit extending from a suitable source of supply indicated as + in Fig. 4, through the main controller M. C., the reversing controller Rev. C. and the winding 80 to ground. If not already therein, the pneumatic engine controlled by winding 80 at once operates the reversing switch to the forward position to connect the motor field windings in the proper relation for forward rotation. Also in case the series-parallel switch, S. P. Sw., is in the series-parallel or the parallel position, the right-hand operating winding 82 is energized from the source + through the reversing controller, the selective controller, the conductor 101, the left-hand winding 82, the conductor 102, and the auxiliary contact 22_a of the electromagnetic contactor 22 to ground. This effects operation of the series-parallel switch to close the contactors 41, 48, 50, 53, 55 and 58 as indicated for the first step of series motoring in the sequence chart shown in Fig. 3 and thereby interconnect the motors in the series relation.

Operation of the main controller into the first position *p*—1 also energizes the operating windings of the electromagnetic line contactors 1, 6, 7 and 8. With the circuit

breaker C. B. in the closed position, the resulting closure of the line contactors connects the driving motors to the trolley in the series relation, and the motors at once 5 start to drive the locomotive in the forward direction at the minimum speed.

The power circuit for the series operating relation of the motors is shown schematically in Fig. 7 and may be traced in Fig. 1 10 from the trolley T through the circuit breaker C. B., the line contactor 1, the resistors R_{11} — R_{17} , the line contactor 7, the resistors R_{21} — R_{25} , the line contactor 8, the resistors R_{32} — R_{35} , the line contactor 6, the 15 armatures A_1 — A_2 , the contactor 41, armature A_3 , contactor 48, armatures A_5 — A_6 , contactor 50, armature A_4 , field F_4 , contactor 53, fields F_5 and F_6 , contactors 55 and 70, field F_3 , contactor 58, field F_1 and F_2 , 20 and through the contactor 67 to ground.

To accelerate the locomotive, the main controller M. C. is advanced notch by notch from the first position. During this advancement of the main controller, the energizing circuits for the several resistance contactors 11 to 35 are established in a predetermined sequence so as to close the same at the respective controller positions 2 to 16 as indicated in the sequence chart 25 in Fig. 3. The various energizing circuits for the operating windings of the resistance contactors are shown in Fig. 4, and will be apparent to those skilled in the art without detailed description. Advancement of the 30 main controller M. C. to the operating positions $p17$ and $p18$ establishes energizing circuits for the field shunting contactors 71 to 78 as indicated in the sequence chart.

If desired motoring operation may be 40 started with the motors connected directly in the series-parallel or the parallel speed combination without passing through a lower speed combination.

Series-parallel operation.

Thus in case the selective controller is operated to the series-parallel position indicated as S. P. with the main controller in the off position or before the main controller M. C. is advanced beyond the first notch, the interconnection of the motors in the series-parallel relation as shown in Fig. 8 is immediately accomplished. Under these 50 conditions the operation of the selective controller into the series-parallel position energizes the left hand magnet valve winding 83 through a circuit extending through the conductor 103, the left hand winding 83, conductor 104, and the auxiliary contact 31_c of the electromagnetic contactor 31 to ground. The contactor 31 remains open and its auxiliary contacts are maintained closed while the main controller is in the off position or in the first notch. With the 55 series-parallel switch in the series position,

energization of winding 83 causes movement of the series-parallel switch toward the series-parallel position. As this position is approached, the ground connection of the left-hand magnet valve winding 83 is transferred from the auxiliary contact 31_c on switch 31 to the ground segment 201 of the auxiliary contacts with which the series-parallel switch is provided. A slight further advance of the series-parallel switch 60 completes the energizing circuit for the right-hand magnet valve winding 82 extending from the selective switch Sel. C. through the conductor 103, the right-hand winding 82, and the ground segment 201. With the 65 windings of both magnet valves 82 and 83 energized, the operating pistons of the pneumatic engine are balanced, thereby stopping the advance of the series-parallel switch substantially in the series-parallel position. 70

Referring to the sequence chart under the heading "Starting from rest in series parallel", it will be observed that the series-parallel contactors 41, 45, 46, 48, 49, 50, 53, 55, 56, and 58 are operated to establish the 75 series parallel motoring connections with all of the resistance in the circuit to limit the motor current. As indicated schematically in Fig. 8, the motors now are connected in parallel groups, each containing three motors, 80 the motors A_1 , A_2 , and A_3 , with their respective field windings F_1 , F_2 and F_3 receiving current from the trolley T through the circuit breaker C. B. contactor 2, the resistances R_{21} — R_{25} , contactor 8, the resistances 85 R_{32} — R_{35} , contactor 6, armatures A_1 and A_2 , contactor 41, armature A_3 , contactors 45 and 46, field F_3 , contactor 58, fields F_1 and F_2 , contactor 67 to ground. The motors A_4 , A_5 and A_6 receive current through the contactor 1, 90 resistors R_{11} — R_{17} , contactor 4, contactor 49, armatures A_5 and A_6 , contactor 50, armature A_4 , field F_4 , contactor 53, fields F_5 and F_6 , contactors 55 and 70, field F_3 , contactors 57 and 67, to ground. Contactor 10 also is 95 closed connecting resistors R_{11} — R_{17} in multiple with resistors R_{21} — R_{25} and R_{31} — R_{35} which are in series with each other. The resistors are so proportioned that with all of the resistors in the motor circuit, as shown 100 in Fig. 8, the current is limited to a suitable safe value even when the series parallel motoring connections are established with the motors at rest.

Advancement of the main controller M. C. 105 through the successive operating positions $p2$ to $p18$ causes operation of the resistance contactors 11—35, and also the field shunting contactors 71—78, to short circuit the corresponding resistors R_{11} — R_{35} , and accelerate 110 the motors in substantially the same manner as described in the full series acceleration of the locomotive. However, it may be noted at this point that in a series-parallel acceleration of the motors certain of the resist- 115 120 125 130

ance controlling contactors, such as contactors 14, 15, 21 and 25 are energized at different notches on the main controller than during a series acceleration. This variation in the sequence in which the resistance contactors are closed is accomplished through the agency of the auxiliary segments on the series-parallel switch and enables the motor torque to be varied in substantially equal increments in each speed relation as will be explained more fully hereinafter.

Parallel operation.

If the motoring operation is started in the parallel speed combination, as may be desired with the locomotive on a relatively steep down grade or coasting, this is accomplished with the main controller M. C. in either the off or the first notch by moving the selective controller into the parallel position shown as *p*. The selective controller in position *p* establishes a circuit extending through the conductor 105, the right hand magnet valve winding 83, the conductor 106, and the auxiliary contact 31₄ on contactor 31. With the series-parallel switch in either the series or the series-parallel position, the pneumatic motor immediately starts operation to the full parallel position. As this position is approached, the energizing circuit of the right hand magnet valve winding 83 is transferred to the ground segment 201 in the same manner as previously described. The resulting parallel motoring connections are shown schematically in Fig. 9 with all of the current limiting resistance in the motor circuit. In this case the full resistance limits the current to a safe value even though the parallel connections are established with the motors at rest. This again permits operation of the main controller M. C. to remove the resistance from the motor circuits and shunt the motor field windings as in the series or series-parallel acceleration. In this case the resistance contactors again are closed in a slightly different sequence upon the operation of the main controller M. C. through the same notches in order to vary the motor torque in substantially equal increments in the parallel operating relation of the motors.

In the parallel speed combination the motors are operated in three parallel groups, each composed of two motors. The motors A₁ and A₂, Fig. 1, receive current through the contactor 3, the resistor R₃₁—R₃₅, contactor 6, armatures A₁ and A₂, contactors 43 and 44, the field windings F₁, F₂, and the contactor 67 to ground. The second parallel motor circuit extends through the contactor 2, resistances R₂₂—R₂₅, contactor 5, contactor 42, armature A₃, contactor 47, armature A₄, field F₄, contactor 54, field F₃, and contactors 57 and 67 to ground. The third parallel motor circuit extends through

contactor 1, resistors R₁₁—R₁₇, contactor 4, contactor 49, armatures A₅ and A₆, contactors 51 and 52, fields F₅ and F₆, and contactors 56 and 67 to ground. Contactors 9 and 10 are also closed connecting resistors R₁₁—R₁₇, R₂₁—R₂₅ and R₃₁—R₃₅ in multiple with each other.

Transition control.

It should be noted that with the main controller in either the off position or the first notch, the interconnection of the motors in either the series, series-parallel or the parallel relation, is accomplished by the series-parallel switch immediately upon the operation of the selective controller to the corresponding position. Transition from the parallel or the series-parallel into the full series relation also may be accomplished with the main controller M. C. in any one of the first four notches. However, it will be evident that when an appreciable amount of resistance has been removed from the motor circuits by operation of the main controller M. C., it is undesirable from the operating standpoint to permit free transition of the motors between the several speed combinations. This is due to the fact that with the regulating resistance removed from the circuits, the large variation in motor torque occurring upon the change in the interconnection of the motor imposes severe jolts or shocks upon the locomotive and train, which obviously are harmful to the equipment and hence undesirable.

In accordance with the present invention, the transition of the motor connections between the several speed combinations is automatically controlled so that the transition is accomplished only when the resulting change in motor torque is of limited value. In order properly to control the transition of the motors during acceleration through the series and series-parallel to the parallel speed combination, the electroresponsive relay R₁ shown in Fig. 4 is arranged to cooperate with the selective controller and the main controller in such a manner that while the selective controller may be operated to a higher speed combination position with the main controller M. C. in any one of its operative positions, nevertheless the actual transition into the speed combination selected is not made until the main controller M. C. has been operated to insert a suitable amount of resistance in the motor circuits. Likewise, in transition during deceleration from the high speed parallel combination through the series-parallel to the low speed series combination, the electroresponsive relay R₂ shown in Fig. 4 insures that the transition as preselected by operation of the selective controller is made only when the proper amount of resistance has been inserted into the motor circuits. Conse-

quently the acceleration or deceleration of the locomotive is smooth and gradual, and there is no appreciable shock imposed upon the locomotive or the train during the transition of the motor connections.

Transition—series to series-parallel.

A typical acceleration of the motors from the series speed combination, through the 10 series-parallel speed combination, to the parallel speed combination is as follows:

Let us assume that a considerable portion of the resistance in the circuit with the motors in the series speed combination has been 15 removed by operation of the main controller M. C. to one of its higher speed positions such as, for example $p-16$, and that it is now desired to change the motors into the series-parallel speed combination to permit 20 higher speed operation. The selective controller Sel. C. may be operated to the series-parallel position immediately. The motors, however, continue to operate in the series relation with the resistance removed from the 25 circuit.

When the selective controller is operated to the series-parallel position an energizing circuit for the relay R_1 is established extending through the conductor 103, the segment 202 of the series parallel switch, segment 203 of the braking switch, and thence through the operating winding of the relay R_1 to ground. The relay R_1 at once closes its contacts and completes the circuit 30 through which the electro-magnetic contactors 2, 17, 25 and 35 are maintained energized even though the main controller is operated from the notch $p-16$ towards the off position. The maintaining circuit for 35 contactor 2 may be traced from the main segment of the controller M. C. through the conductor 107, the contact R_{1a} , contact 2_b , segment 219 in series-parallel switch, to the operating winding of electromagnetic switch 40 2. The maintaining circuit for the other contactors extends from the main segment of the controller M. C. through the conductor 107, the contact R_{1b} , the auxiliary contacts 35, thence through the operating windings 17, 35, and through contact 35_b and operating winding 25, in parallel circuits to the conductor 108, segment 204 of the main controller to ground. The main controller M. C. then is moved from the running position $p16$ to the position $p5$ without disturbing in any way the full series operation of the driving motors.

As soon as the main controller M. C. reaches position $p5$, the maintaining circuit 45 for the electromagnetic switches 17, 35 and 25 is interrupted, since the contact segment 204 of the controller M. C. leaves the stationary contact cooperating therewith as the main controller passes from position $p6$ to position $p5$. This causes the insertion of

suitable portions of the resistors $R_{11}-R_{17}$, $R_{21}-R_{25}$ and $R_{31}-R_{35}$ into the motor circuit, as indicated in Fig. 10. In this case the entire amount of resistance is not necessary to limit the motor current to a safe value 70 since the series parallel connections are established with the motors already in operation. Due to the energization of the winding 83, the series-parallel switch operates to shift the motor connections from the series to series-parallel relation. At the same time, the left-hand magnet valve winding 83 is energized through a circuit extending from the selective controller Sel. C. through the conductor 103, the left-hand magnet valve winding 83, the segment 200, the conductor 109, auxiliary contact 2_a of the contactor 2, segment 206 of the braking switch, conductor 110, thence through segment 205 of the main controller to ground. 80

Due to the fact that the resistors are inserted in the respective motor circuits as just pointed out, before the motors are transferred from the series to the series-parallel combination, the motor current is maintained substantially the same after the transition is completed, and there is no appreciable jar or jolt imposed upon the locomotive by the transition.

The motors are accelerated in the series-parallel relation by operation of the main controller M. C. to remove the resistances from the motor circuits in an obvious manner.

Transition, series-parallel to parallel.

If the acceleration of the locomotive is to be continued with the motors in the parallel speed combination, the selective controller Sel. C. may be operated to the parallel position P at any time during the acceleration of the motors in the series-parallel relation. In the parallel position P, the selective controller again establishes an energizing circuit through the relay R_1 . The relay circuit now extends through the conductor 105, the segment 207 of the series-parallel switch, the segment 203 of the braking switch, thence through the winding of the relay R_1 to ground. The relay R_1 at once closes its contacts preparatory to re-establishing and maintaining a circuit for the operating windings of the electromagnetic contactors 3, 17, 25, and 35 when the latter is closed by operation of the main controller to position 110 $p16$. In this way the resistance in the motor circuit is maintained short circuited while the main controller M. C. is returned to the position $p5$ to effect the transition into the parallel speed combination of the motors. 115 This maintaining circuit for the resistance control contactors 17, 25, and 35 is interrupted when the segment 204 leaves its cooperating stationary contact as the controller M. C. is moved from notch P_6 to notch P_5 . Conse- 120 130

- quently the several groups of resistances which were maintained short circuited by the contacts 17, 25, and 35 are reinserted in the motor circuit before the transition of the 5 motors into the parallel relation takes place. However, the resistance controlling contactors 21, 22 and 31 remain closed to short circuit the corresponding resistors. When the main controller reaches the position p_5 the 10 right hand magnet valve winding 83 is energized through a circuit including the selective controller Sel. C., the conductor 103, the right-hand magnet valve winding 83, the contact segment 208 of the series-parallel 15 switch, the auxiliary contact 3_a of the contact 3, the segment 206 of the braking switch, conductor 110, and thence through the segment 205, to ground. The series-parallel switch is at once operated to interconnect 20 the motors in the parallel relation.

The several groups of resistances are removed from the motor circuits upon operation of the main controller M. C. in the manner previously described to cause operation 25 of the motors at maximum speed in the parallel relation.

The motor circuit may be interrupted while the motors are connected in either the series or parallel relation simply by operation 30 of the controller M. C. to the off position, thereby interrupting the energizing circuit of all the electromagnetic contactors which control the motor circuits. Thus it will be seen that no transition of the motors 35 in stopping is necessary.

Transition, parallel to series-parallel.

However, should the service conditions under which the motors are operated vary so 40 that it becomes desirable to transfer from the parallel speed combination to the series-parallel combination, as for example in ascending a heavy grade. This readily may be accomplished without interrupting the 45 continuity of the motoring effort. The relay R_2 cooperates with the selective controller and the main controller in effecting the transition without any such changes in the motor current and torque as would impose undue 50 shocks or strains upon the equipment.

Thus with the motors operating in the parallel speed combination, the selective controller Sel. C. may be moved any time to the series-parallel position in anticipation of the 55 operation of the motors in the lower speed combination. When the main controller is returned to the notch P_c the electromagnetic resistance controlling contactor 23 is thereby deenergized, the operating winding and 60 relay R_2 operates to close the auxiliary contacts R_{2a} and open the others. The opening of these contacts opens the operating circuits of certain of the resistance controlling contactors 11-35 so that they are prevented 65 from closing when the main controller is

moved out again to notch p_{14} which is the notch in which the transition takes place. The main controller M. C. is then operated to successively deenergize certain of the electromagnetic resistance controlling contactors 70 11-35 in the reverse order from that in which they are energized as shown in the sequence chart, thus inserting resistance in the motor circuits to decelerate the locomotive. 75

The operating winding of relay R_2 is energized through a circuit extending from the selective controlled through the conductor 80 103, the segment 209 of the series-parallel switch, conductor 111, the auxiliary contact 23_a which is closed when the contactor 23 opens, and the winding of relay R_2 to ground. The resulting operation of relay R_2 interrupts the energizing circuit for the electroresponsive contactors 11, 12, 13, 15, 16, 85 17, 23, 24, 25, 32, 33, 34, and 35 by opening the connection for the operating windings of the several respective contactors. Thus, upon the advancement of the main controller M. C. from the notch p_6 , no change in 90 the motor circuit occurs until notch p_{14} is reached.

In the notch p_{14} of the main controller the contact segment 210, together with the stationary contact cooperating therewith, completes the energizing circuit for the magnet valve winding 82 to effect operation of the series-parallel switch from the parallel position to the series-parallel position. The circuit may be traced from the series-parallel segment of the selective controller through the conductor 103, the right-hand magnet valve winding 82, the interlocking segment 211 of the series-parallel switch, the contact R_{2a} which is closed when the relay R_2 is energized, the segment 212 of the braking switch, and thence through the contact segment 210 of the main controller to ground. During the resulting operation of the series-parallel switch to the series-parallel position, the energizing circuit of the right hand magnet valve winding 82 is transferred from the segment 211 to the grounded segment 201 and the left-hand magnet valve winding 83 also is automatically energized through the conductor 103 and the ground segment 201 of the series-parallel switch to balance the pistons of the operating pneumatic engine, thereby stopping the series-parallel switch in the series-parallel position. 110 115 120

At substantially the same time the energizing circuit of the relay R_2 is interrupted by the disengagement of contact segment 209 from the stationary contacts cooperating therewith. The relay R_2 at once returns to the position in which it is shown in Fig. 4, and thereby reestablishes the energizing circuits for the electromagnetic contactors 11, 12, 13, 23, 24, 32, 33 and 34, 125 130

which were maintained deenergized during the movement of the main controller M. C. from position $p6$ to position $p14$. The resulting operation of these electromagnetic contactors is to remove a large share of the resistances from the motor circuits as soon as the transition of the motors from the parallel speed combination to the series-parallel speed combination is completed, and consequently the motor current and torque are not varied materially.

The precise manner of accomplishing the transition of the motor connections from the parallel relation to the series parallel operating relation without interrupting the continuity of the motor driving torque is indicated in the portion of the sequence chart of Fig. 3 under the heading of "Turning off." This chart shows the exact sequence in which the various circuit controlling switches indicated in Fig. 1 are operated to shift the motor connection while maintaining at least a portion of the motor connected in the supply lines at all times during the transition period. The principal steps involved in this transition are indicated schematically in Figs. 14, 15, 16 and 17. Fig. 14 shows the motors connected for operation in the parallel relation with the transition resistor R_{44} and R_{52} short circuited. The several groups of motor torque and speed controlling resistors R_{11} — R_{17} , R_{21} — R_{25} and R_{31} — R_{35} also are short circuited to permit full high speed operation.

Upon the manipulation of the main controller MC and the selector controller SELC to affect the transition from the parallel operating relation to the series parallel operating relation in the manner described above, the initial change in the motor connections as shown in Fig. 15 is effected. In this step it will be noted that the several groups of torque and speed resistors are reinserted in the motor circuits. In addition, the transition resistors R_{44} — R_{52} are inserted respectively in series with the motor armatures A_1 — A_2 and A_5 — A_6 . Also the motor armatures A_3 — A_4 and field windings F_3 , F_4 are entirely disconnected from the supply circuit as indicated. However, the remaining motors A_1 , A_2 and A_5 , A_6 in the circuit serve to drive the locomotive with a fairly uniform torque since the locomotive speed necessarily is decreasing.

The next step in the transition is the connection of the armature A_4 and its field winding F_4 across the transition resistor R_{52} and the connection of the armature A_3 and its field winding F_3 across the transition resistor R_{44} . This step is illustrated in Fig. 16.

The transition is completed by disconnecting one end of the transition resistors R_{44} and R_{52} from the circuit, thereby inserting the corresponding motors A_3 and A_4 in the

circuit. Thus it will be seen that the continuity of the driving torque of motors A_1 , A_2 and A_5 , A_6 is maintained throughout the entire transition.

It may be noted that the transition is intentionally made on notch $p14$ of the controller so that a portion of the accelerating resistance will be left in the motor circuits after the transition is completed. This is one of the novel features of the control and the reasons for doing this will be more fully disclosed hereinafter. Briefly the resistance which is left in the motor circuits acts as a cushioning resistance and reduces any tendency of the current in the motor circuits to increase which otherwise might take place should the trolley voltage be increased due to the transition on the locomotive.

The locomotive is now operating in notch $p14$ of the series-parallel combination of the motors. If it is desired to operate in the full series-parallel running position the controller may be moved to notches $p16$, 17 or 18 in the usual manner for accelerating the locomotive.

If it is desired to decelerate the locomotive, the main controller M. C. is moved progressively from position $p14$ toward the off position.

Transition, series-parallel to series.

If, in the meantime, the operator has decided to continue the deceleration of the locomotive through the series speed combination of the motors, the selective controller Sel. C. is moved to position S. Under this condition, when the main controller reaches position $p6$, substantially the same sequence of operation as previously described in the transition from parallel to series-parallel is repeated. The relay R_2 is energized through a circuit extending from the series contact segment of the selective controller, the conductor 101, the series-parallel switch interlocking segment 220, conductor 111, the auxiliary contact 23_c, thence through the winding of the relay R_2 to ground. As previously described, the relay R_2 maintains the energizing circuit of the resistance controlling contactors 11, 12, 13, 15, 16, 17, 23, 24, 25, 33, 34, and 35 open while the main controller M. C. is advanced from position $p6$ to position $p14$. In the latter position, the main controller segment 210 establishes an energizing circuit for the left-hand magnet valve winding 82 to operate the series-parallel switch from the series-parallel position to the series position. This circuit extends from the series segment of the selective switch which is energized from the source + through the conductor 101, left-hand magnet valve winding 82, the series-parallel switch interlocking segment 213, the auxiliary contact 3_c of the electromagnet line contactor 3, contact R_{2a} 130

of the relay R_2 , the braking switch segment 212, thence through the main controller segment 210 to ground. As the series-parallel switch operates to the series position, the energizing circuit of the left-hand magnet valve winding 82 is transferred from the interlocking segment 213 to the ground segment 201. Also the relay R_2 is deenergized when the series-parallel switch segment 220 disengages with its cooperating contacts. This causes the resistance contactors 11, 12, 13, 23, 24, 33 and 34 to close and short circuit corresponding sections of resistors R_{11} — R_{17} , R_{21} — R_{25} , R_{31} — R_{35} . As stated under the transition parallel-series parallel not all of the accelerating resistance is short circuited when these contactors close and the locomotive is operating in notch $p14$ with the motors in the series combination. Should it be desired to operate the locomotive in the full series running positions the main controller may be moved out to notches $p16$, 17 or 18 in the usual manner for accelerating the locomotive. Should it be desired to decelerate the locomotive still further the main controller M. C. may be returned from position 14 to position $p1$ to deenergize the contactors 11 to 35, thereby inserting all the resistances in the motor circuits to obtain minimum speed operation in the series connection.

It should be noted that the motor circuit may be interrupted to stop the locomotive at any time during decelerating operation with the motors connected in either the parallel, the series-parallel, or the series relation, simply by returning the main controller M. C. to the off position. This may be done irrespective of previous operation of the selective controller, since all of the electromagnetic contactor circuits are interrupted with the main controller in the off position.

From the foregoing it will be evident that the control system embodying the present invention permits the interconnection of the motors to be changed from either a lower speed combination to higher speed combinations, or from a higher speed combination to lower speed combinations in a manner which insures a gradual and smooth acceleration or deceleration of the locomotive. Consequently the speed of the locomotive may be varied at will to conform with the service conditions encountered without danger of bunching the slack in the trains as would occur in case the motor circuit were interrupted during transition of the motors between the various speed combinations. Furthermore, by not short circuiting all the accelerating resistance after a transition from a higher speed to a lower speed combination of the motors is completed a novel feature is introduced which

is an improvement over the present method of making such transitions.

Regenerating braking operation.

The braking operation of the motors is under the joint control of the selective controller Sel. C., the main controller M. C., and the braking controller Br. C., and the reversing controller of course determines the direction of operation. It will be observed that the braking controller is provided with suitable segments for controlling the exciter field resistance Ex. F. R. and also for controlling the operation of the exciter field switch 86, as well as the magnet valve windings 84 and 85 of the braking switch Br. Sw. Regenerative braking operation may be initiated in the following manner. Assuming that the motors are operating in the full series relation (M. C. in notch $p16$), the main controller M. C. is returned to the first position, thereby deenergizing the several groups of electromagnetic resistance controlling contactors, including the contactor 31. The braking controller Br. C. then may be operated into any one of the braking positions b_1 — b_{15} , depending upon the estimated value of field excitation required in the particular service conditions under which the locomotive is operated. Assume that the braking controller is moved into the braking position b_6 . As the braking controller passes through position b_1 , the operating winding of the exciter field switch 86, together with the magnet valve windings 84 and 85 of the braking switch, are energized in parallel through a circuit extending from the source + through the main segment of the main controller M. C., the conductor 112, auxiliary contact 31_a of the resistance controlling contractor 31, and thence in parallel circuits through the magnet valve windings 84; the segment 215 of the series-parallel switch, the magnet valve winding 85, the segment 214 of the braking switch; and through the auxiliary contact C. B.₁ of the circuit breaker, the operating winding of field switch 86 to the conductor 113, which is grounded through the segment 216 of the braking controller. This results in the energization of the exciter shunt field indicated as Ex. S. F. through the circuit extending from the source + through a portion of the resistance Ex. F. R., the contact F. C.₁ of switch 86, resistance P. R., and the field winding to ground, the value of the current in the field winding depending upon the position of the braking controller Br. C. At the same time the pneumatic operating engine of the braking switch functions to move the switch into the intermediate series and series-parallel position indicated as $-sp$. As previously pointed out, the magnet valve controlled by the double windings 84 and 85 is of the type which is biased to admit air

to the pneumatic engine when the windings are deenergized. Consequently the braking switch pneumatic engine functions to move the braking switch into the intermediate 5 series and series-parallel position. As the intermediate position is reached, the pneumatic valve winding 85 is deenergized by the disengagement of the segment 214 from the stationary contacts operating therewith, 10 thus balancing the pistons of the pneumatic engine, thereby stopping and maintaining the braking switch in the intermediate position. With the motors operating in the 15 series relation, movement of the braking switch into the intermediate position closes the cam contactors 62, 63, 65, and 69 and opens cam contactor 70 to thereby connect exciter E to the motor circuits and establish ground connections between the motor 20 armatures and their respective field windings to permit over-excitation of the latter from the exciter generator E. The resulting series regenerative braking connections are shown schematically in Fig. 11.

25 Due to the fact that all the resistance is inserted in the motor circuits when the main controller M. C. is returned to position ρ_1 , the current of the circuit is limited to a small value. Preferably the braking controller Br. C. is set at such a position that the shunt field winding of the exciter generator E is overexcited only a slight amount, consequently, the overexcitation of the motor field windings is of such value that the 30 motors continue to receive current from the trolley T. The main controller then is advanced from the position ρ_1 to position ρ_16 to remove the resistance from the motor circuit and by properly timing this operation it may be performed when the motor 35 current input from the line is substantially zero in amount. The braking controller then may be operated to increase the over-excitation of the motor field windings to cause the motors to return current to the trolley T, and thereby produce a regenerative 40 braking action of the desired value.

45 Regenerative braking with the motors in the series relation, as shown in Fig. 11, is ordinarily employed at slow speeds of the locomotive. In case braking at higher speeds is desired, the motors are interconnected in the series-parallel or the parallel speed relation. As it is undesirable to effect 50 transition of the motors from one speed combination into different speed combinations while the motor field windings are overexcited due to the fact that some of the motors necessarily are short circuited during the transition, it is necessary to hold or 55 retard the train by means of the customary form of air-brake equipment, and interrupt the motor circuit during the transition from one speed combination to a different speed

60 combination in regenerative braking operation.

65 Thus, with the motors in the series braking relation as previously described, the change into the series-parallel braking relation, as shown in Fig. 12, is accomplished 70 by returning the braking controller Br. C. to the normal or motoring position M, shutting off the main controller, moving the selective controller into the series-parallel 75 position, and bringing the main controller into notch ρ_1 . The braking controller then may be moved into the desired braking position to energize the exciter shunt field winding, and cause operation of the braking switch to the intermediate series-parallel 80 position in the manner just described.

85 For parallel braking operation, as shown in Fig. 13, substantially the same manipulation of the controls is required, except that the selective controller is moved into the parallel position.

Variation in resistance contactor sequence.

90 The variation in the sequence in which certain of the resistance control contactors are closed upon operation of the main controller through the same series of positions, depending upon the particular speed relation in which the motors are operating, has been previously noted. The manner in 95 which this is accomplished will be apparent from a careful inspection of the control circuits illustrated in Fig. 4. For example, it will be seen that the operating winding of the resistance controlling contactor 21 is 100 energized in position ρ_3 of the main controller when the series-parallel switch S. P. Sw. is in the series position s. The circuit may be traced from the supply source + through the main controller, the conductor 114, the auxiliary contact segment 217 of the series-parallel switch and thence through the operating winding of contactor 21 to ground. In this case, as indicated in the 105 sequence chart, only the energizing circuit for contactor 21 is closed upon the operation of the main controller to its third notch.

110 When the series-parallel switch is operated to the series-parallel position, contactor 21 is energized on the second notch (ρ_2) of the main controller M. C., and at the same time resistance controlling contactor 31 also is energized. In this case the circuit extends from the main controller M. C. through the conductor 115, and thence to the operating winding of contactor 31 and the operating winding of contactor 21 in parallel circuit to ground, the circuit of the contactor 21 extending through the central portion of auxiliary contact segment 217. 115 With the resistors R_{21} and R_{31} properly proportioned, the variation in the motor torque 120 resulting from the simultaneous operation

of the two contactors in the series-parallel operating relation of the motors produces a variation in the motor torque which is substantially equal to the variation produced at the same notch of the main controller in the full series operating relation of the motors.

In the parallel combination of the motors the resistance contactor 21 is closed upon operation of the main controller M. C. to a still different position, namely, position p_5 , and the closure of contactor 21 occurs simultaneously with the closure of contactor 22. In the parallel of the motors the energizing circuit for contactor 21 extends from the main controller through the conductor 116, the auxiliary contact segments 218 and 217 of the series parallel switch and the operating winding of contactor 21 to ground, the winding being energized in parallel circuit 20 with the winding of contactor 22.

The variation in the sequence of closure of the several other resistance controlling contactors 14, 15, 21, 25 and 32 is accomplished in a similar manner and further detailed description of the various energizing circuits for these contactors is deemed unnecessary. By thus varying the sequence in which the several contactors are operated and by properly proportioning the value of the resistance controlled thereby, it will be apparent that the motor torque may be varied in each operating relation of the motors in substantially equal increments, thereby insuring a smooth acceleration and deceleration of the locomotive in all connections of the motors.

Special provision to prevent excessive current during transitions from a higher speed combination of the motors to a lower speed one.

It should be noted that the transitions from parallel to series-parallel, and from series-parallel to series, are made on notch p_{14} of the main controller. This insures that after the transition has been completed, there is still a certain amount of resistance left in series with the motors. From a practical operating standpoint, this is a marked improvement over the usual form of control, in which the resistance is entirely short circuited as soon as the transition is completed since with a large size locomotive, especially those intended for freight service, the current input to the locomotive is often a very large percentage of the total load on the two substations next adjacent to the locomotive and train. The current input is naturally larger with the locomotive operating in a higher speed connection of the motors than in a lower speed connection. Under these conditions if a transition is made from a higher speed connection of the motors to a lower one, the current input to the locomotive is greatly decreased. (On a six motor,

three speed locomotive P—SP decreases the current to $\frac{2}{3}$ of former value and Sp—S to $\frac{1}{2}$.) Reduction of this current input causes the voltage to rise at the locomotive if it is any great distance from the substation, and this amount of rise is often considerable.

If the accelerating resistors are entirely short circuited immediately after a transition under these conditions the current input per motor will be increased considerably beyond that which would occur with a transition at normal voltage and may cause a shock to the locomotive and train. By leaving a portion of the accelerating resistors connected in the motor circuits during and after the transition has taken place, any increase in the motor current which may occur due to increase in line voltage due to the transition is effectively checked. While this same result may be obtained in the well known progressive controller form of control by moving the controller into one of the lower speed resistance notches before the series-parallel switch has a chance to throw, there is nothing in the control which requires the operator to do it. Nor is it so easy to accomplish this result as with this selective type of control.

Construction of the operating handle of main controller.

In order to enable the main controller to be conveniently handled by the operator in performing the previously described controlling operations, it is desirable although not absolutely necessary to provide the arrangement of the operative handle shown in Figs. 5 and 6. In addition to the ordinary latch engaging with a notched dial ring, having each notch corresponding to one of the positions 1 to 18 of the main controller which it is the usual practice to provide on locomotive controllers although not illustrated, the three stops S—1, S—2, and S—3 are provided as shown in Figs. 5 and 6. Stop S—1 preferably is located on top of the dial ring while stops S—2 and S—3 are located on the opposite side.

The handle 300, Fig. 6, is provided with a latch 301 which is held by a spring 307 so that one face of this latch 304 normally bears against the top side of the dial ring 302 while the other face 303 of the latch 301 is held by spring 307 clear of the lower face of the dial ring 302.

Stop S—1 is arranged to engage with face 304 of latch 301 when the handle 300 is moved to the position corresponding to notch p_{16} of the main controller (Fig. 4). This indicates to the locomotive operator that the controller has been brought into the full field running position. In order to go beyond notch p_{16} into the reduced or shunted field running positions p_{17} and p_{18}

it is necessary for the operator to press the button 305 in the end of the handle 300 which brings the rod 308 into engagement with latch 301 compressing spring 306 and 5 raising face 303 into engagement with the lower side of the dial ring 302 and raising face 304 out of engagement with the stop S-1, thus permitting movement of the handle into notches p17 and p18. This construction is old and well known to those skilled in the art.

When transitions going from a lower speed combination of motors to a higher speed one are to be made it is necessary first to bring 15 the controller into the notch p16 and then to move it to notch p5. The stop S-2 is so located as to engage with face 303 of latch 301 when the handle 300 is moved back into notch p5 providing button 305 is pressed in 20 raising face 303 of latch 301 into engagement with the under side of the dial ring. As the steps p15 to p6 inclusive produce no change in the locomotive torque during this operation it is intended that the operator shall 25 press the button 305 in the handle on notch p16 and hold it in, moving the controller rapidly toward the off position. Engagement of the handle with stop S-2 will indicate when the controller reaches the notch 30 p5 on which the transition to a higher speed combination of the motors takes place.

Similarly stop S-3 is arranged to engage with face 303 of latch 301 when handle 300 is brought into notch p14. This enables the 35 button 305 to be depressed, held depressed and the controller handle moved rapidly from notch p6 to notch p14 when making transitions from a higher speed combination of the motors to a lower speed one.

40 The use of stops S-2 and S-3 greatly facilitate the manipulation of the controller during transitions.

What I claim as new and desire to secure by Letters Patent of the United States, is,—

45 1. The combination with a plurality of electric motors adapted for operation in a plurality of speed relations, of means for controlling the speed relation in which the motors are to operate, and independently 50 operable means for controlling the operating speeds of the motors and arranged to cooperate with said first means for controlling the interconnection of the motors in a lower speed relation without interrupting the continuity of motor torque when the 55 motors are operating in a higher speed relation.

60 2. The combination with a plurality of electric motors, of switch mechanism for interconnecting the motors for operation in each of a plurality of speed relations, separately operable switch mechanism for varying the speed of the motors in each of said 65 relations, and means cooperating with said separately operable switch mechanism for

causing operation of the first switch mechanism to change the interconnection of the motors to a lower speed relation without interrupting the continuity of motor torque upon a predetermined operation of said 70 separately operable switch mechanism when the motors are operating in a higher speed relation.

3. The combination with a plurality of electric motors, of switch mechanism for 75 interconnecting the motors for operation in each of a plurality of speed relations, separately operable switch mechanism having a plurality of operative positions for varying the speed of the motors in each of said 80 relations, and means depending upon operation of said speed controlling switch mechanism into at least two of said operative positions for causing operation of the said first switch mechanism to change the interconnection of the motors to a lower speed relation without interrupting the continuity of motor torque when the motors are operating 85 in a higher speed relation.

4. The combination with a plurality of electric motors adapted to be interconnected for operation in each of a plurality of speed relations, of means for selecting the speed relation in which the motors are to be operated, independently operable means for controlling the speed of the motors in each of said speed relations, and switch mechanism arranged to be jointly controlled by said means to change the interconnection of the 90 motors to each other speed relation when the motors are operating in each of said speed relations without interrupting the continuity of the motor torque.

5. The combination with a plurality of electric motors, of electrically controlled 95 switch mechanism for interconnecting the motors for operation in a plurality of speed relations, a selective controller therefor, an independently operable speed controller for varying the speed of the motors in each of said 100 relations, and connections arranged upon operation of the selective controller to be controlled by said speed controller when the motors are operating in a higher speed relation through which the electrically 105 controlled switch mechanism is operated to change the interconnection of the motors to a lower speed relation without interrupting the continuity of motor torque upon a predetermined operation of said speed controller.

6. The combination with a plurality of electric motors, of power actuated switch mechanism for interconnecting the motors in each of a plurality of speed relations, a controller for varying the speed of the motors in each of said relations, and an independently operable controller arranged to cooperate with said speed controller during 125 operation of the motors in each one of said 130

speed relations for controlling the said power actuated switch mechanism to change the interconnection of the motors to each other speed relation without interrupting 5 the continuity of motor torque.

7. The combination of a plurality of electric motors, of switch mechanism for interconnecting the motors for operation in each of a plurality of speed relations, separately 10 operable switch mechanism for varying the speed of the motors in each of said relations, and connections jointly controlled by said switch mechanisms through which at least a portion of the motors operating in a higher 15 speed relation are maintained energized during a change to a lower speed relation.

8. The combination with a plurality of electric motors adapted for operation in a plurality of speed relations, of means for 20 selecting the speed relation in which the motors are to operate, independently operable means for controlling both the interconnection and the speed of the motors in each of said relations, and connections jointly controlled by said means through which at least a portion of the motors operating in each of said speed relations are maintained energized during a change to each other speed relation.

30 9. The combination with a plurality of electric motors, of power operated transition switch mechanism for interconnecting the motors in each of a plurality of speed relations and arranged to maintain the continuity 35 of the motor circuit during transition each way between said relations, a selective controller operable into a plurality of positions corresponding to said speed relations for controlling the operation of said transition switch mechanism, an independently operated controller for controlling the speed of the motors in each of said relations, and means arranged to be jointly controlled by said controllers when the motors are operating 40 in a high speed relation for operating the said transition switch mechanism to interconnect the motors in a lower speed relation.

45 10. The combination with a plurality of electric motors adapted for operation in a plurality of speed relations, of means for selecting the speed relation in which the motors are to operate, independently operable means for controlling the operating speed of the motors in each relation, and separately operable means controlled by said speed selecting means, one upon operation thereof to select a lower speed relation, and the other upon operation thereof to 55 select a higher speed relation when the motors are operating in each speed relation, for rendering the said speed controlling means ineffective during a predetermined operation thereof.

60 11. The combination with a plurality of

electric motors, of switch mechanism for interconnecting the motors in a plurality of speed relations, a speed regulating resistor arranged to be connected in the motor circuit in each of said relations, means for controlling said resistor to vary the motor speed, and means cooperating with said resistor controlling means when the motors are operating in a higher speed relation for rendering the said controlling means ineffective to control said resistor and for causing operation of said switch mechanism to interconnect the motor in a lower speed relation upon a predetermined operation of said resistance controlling means.

65 12. The combination with a plurality of electric motors, of transition switch mechanism for interconnecting the motors in a plurality of speed relations, resistance means for regulating the speed of the motors in each of said relations, a controller for said means, an independently operable controller for selecting the speed relation in which the motors are to operate, and means jointly controlled by said controllers when the motors are operating in a higher speed relation for disabling the control of said resistance means by said first controller upon operation thereof to a predetermined position and for operating the said transition switch mechanism to interconnect the motors in a lower speed relation upon operation of the said first controller to a second predetermined position.

70 13. The combination with a plurality of electric motors, of transition switch mechanism for interconnecting the motors in each of a plurality of speed relations arranged to maintain the continuity of the motor circuit during transition between said relations, a selective controller having a plurality of positions corresponding to the said speed relations, means including a controller operable through a series of positions for varying the motor speed in each of said relations, and means controlled by said controllers when the motors are operating in a higher speed relation whereby operation of the said selective controller to the position corresponding to a lower speed relation renders the said resistance controller ineffective upon operation thereof to a predetermined position and the said transition switch mechanism is operated to reconnect the motors in a lower speed relation upon operation of the speed controller to a second predetermined position.

75 14. The combination with a plurality of direct current series motors, of power actuated transition switch mechanism for connecting the motors in series, series parallel, and parallel relations, independent means operable between a plurality of positions for varying the speed of the motors in each of said relations, a selective controller operable into a plurality of positions corresponding

to the operating relations of the motors for controlling said transition switch mechanism, and means jointly controlled by the said speed controlling means and the said selective controller when the motors are operating in a higher speed relation and the said selective controller is operated to a lower speed position for rendering the said independent means ineffective to control the speed of the motors during operation thereof from one position to a second position and for causing operation of said power actuated switch mechanism to interconnect the motors in the lower speed relation upon operation 15 of said speed controlling means to said second position.

15. The combination with a plurality of direct current series motors, of power actuated switch mechanism operable between a plurality of positions to interconnect the motors in a plurality of speed relations, a controller for selecting the position to which said power operated switch mechanism is to be operated, an independently operable controller for regulating the speed of the motors in each relation, an electroresponsive relay, connections jointly controlled by the said controllers when the motors are operating in a higher speed relation for establishing an energizing circuit for said relay when the selective controller is operated to a position corresponding to a lower speed relation of the motors and the speed controller is operated to a predetermined position to decrease 35 the operating speed of the motors, and connections controlled by the said relay, during operation of the speed controller to a second predetermined position for maintaining the operating speed of the motor unchanged and 40 for operating the said power actuated switch mechanism to interconnect the motors in a lower speed relation when the said speed controller reaches said second predetermined position.

45. 16. The combination with a plurality of electric motors adapted for operation in each of a plurality of speed relations, of means for controlling the speed relation of the motors, independently operable means for controlling the torque of the motors to vary the operating speed thereof in each relation, and means dependent upon the speed relation of the motors, arranged to cooperate with said independently operable means for 50 varying the torque of the motors in substantially equal increments in each speed relation.

17. The combination with a plurality of electric motors, of switch mechanism for 60 interconnecting the motors for operation in each of the plurality of speed relations, independently operable means for controlling the torque of the motors to vary the speed thereof in each speed relation, and means 65 associated with said switch mechanism for

controlling the said independently operable means to insure variation of the torque of the motors in substantially equal increments in each speed relation of the motors.

18. The combination with a plurality of electric motors, of switch mechanism for interconnecting the motors for operation in each of a plurality of speed relations, a resistor arranged to be connected in circuit with the motors for controlling the torque thereof to vary the speed of the motors in each speed relation, a controller for said resistor, and connections jointly controlled by said switch mechanism and said controller through which the said resistor is controlled 75 to vary the torque of the motors in substantially equal increments in each speed relation of the motors.

19. The combination with a plurality of electric motors, of switch mechanism for interconnecting the motors for operation in each of a plurality of speed relations, resistance means in circuit with the motors in each speed relation, a controller operable through a series of positions for controlling 85 the said resistance means, and means controlled by said switch mechanism and arranged to cooperate with said controller for controlling the said resistance means to vary the torque of the motors in substantially 90 equal increments in each speed relation.

20. The combination with a plurality of electric motors adapted for operation in each of a plurality of speed relations, a controller for controlling the speed relation of the motors, an independently operable controller for controlling the speed of the motors in each relation, and resistance means jointly controlled by said controllers for varying the torque of the motors in substantially 100 equal increments to operate the same at a plurality of speeds in each speed relation.

21. The combination with a plurality of electric motors, of switch mechanism for interconnecting the motors for operation in each of a plurality of speed relations, a plurality of resistors in circuit with the motors in each relation, a plurality of independently operable switches for controlling said resistors, means independent of said first switch mechanism for operating said switches in a predetermined sequence, and means dependent upon the speed relation of the motors for varying the sequence in which 110 said switches are operated.

120 22. The combination with a plurality of electric motors, of selective switch mechanism for interconnecting the motors for operation in each of a plurality of speed relations, a plurality of resistors arranged to be 125 connected in circuit with the motors for varying the torque thereof in each speed relation, a plurality of electrically operated switches for controlling said resistors to operate the motors at different speeds, a con- 130

troller for operating the said switches in a predetermined sequence, and auxiliary switch mechanism associated with said selective switch mechanism and arranged to cooperate with said controller to vary the sequence of operation of said switches to insure variation of the motor torque in substantially equal increments in each speed relation of the motors.

10. 23. The combination with a plurality of electric motors adapted for operation in a plurality of speed relations, of a current regulating resistor for the motors, and switch mechanism for controlling the said resistor and the interconnection of the motors and arranged to maintain at least a portion of the said resistor in circuit with the motors during and after a change in the interconnection of the motors from a higher speed relation 20 to a lower speed relation.

24. The combination with a plurality of electric motors, of switch mechanism for interconnecting the motors for operation in each of a plurality of speed relations, a current regulating resistor for the motors, a controller for controlling said resistor, and means controlled by said controller for causing operation of the said switch mechanism to change the interconnection of the motors 30 from a higher speed relation to a lower speed relation and maintain a portion of said resistor in circuit with the motors during and after the change to the lower speed relation.

25. The combination with a plurality of

electric motors, of switch mechanism for interconnecting the motors for operation in each of a plurality of speed relations, a current regulating resistor for the motors, a controller having a series of operating positions for successively short circuiting portions of 40 said resistor, and means controlled by said controller for causing operation of the said switch mechanism to change the interconnection of the motors from a higher speed relation to a lower speed relation with a portion of said resistor in circuit therewith upon 45 operation of the said controller to an intermediate operating position.

26. The combination with a plurality of electric motors adapted to be interconnected 50 for operation in each of a plurality of speed relations, of means for selecting the speed relation in which the motors are to be operated, a current regulating resistor for controlling the speed of the motors in each of said speed relations, a controller having a series of operative positions for successively short circuiting portions of said resistor, and switch mechanism arranged to be jointly controlled by said selective means and said controller to change the connection of the motors from a higher speed relation to a lower speed relation with at least a portion of said resistor in the motor circuit during and after the change to the lower speed relation. 55

In witness whereof, I have hereunto set my hand this 8th day of December, 1925.

WILLIAM S. H. HAMILTON.

CERTIFICATE OF CORRECTION.

Patent No. 1,684,267.

Granted September 11, 1928, to

WILLIAM S. H. HAMILTON.

It is hereby certified that error appears in the printed specification of the above numbered patent requiring correction as follows: Page 2, line 110, for the word "motor" read "motors"; page 4, line 74, after the word "drawing" insert the word "as"; page 10, line 106, for the word "contractor" read "contactor"; page 14, line 41, claim 9, for the word "operated" read "operable"; line 72, claim 11, for the word "mean" read "means", and line 78, same claim, for "motor" read "motors"; and that the said Letters Patent should be read with these corrections therein that the same may conform to the record of the case in the Patent Office.

Signed and sealed this 20th day of November, A. D. 1928.

(Seal)

**M. J. Moore,
Acting Commissioner of Patents.**
